HYDRAULIC SYSTEM

Thomas F. Stacy, Piqua, Ohio, assignor to The French Oil Mill Machinery Co., Piqua, Ohio

Application February 15, 1939, Serial No. 256,562

16 Claims. (Cl. 103—38)

This invention relates to hydraulic press systems, and particularly to the controls for a press of the type where a fluid under pressure is delivered alternately to the main and pull-back rams, to reciprocate a platen. After a large pressure has been built up, as for example in the main ram, the reversal of the delivery from the pump, either by reversing the pump itself or by a reversible valve, suddenly places the pump on full delivery into the pull-back ram, which is usually smaller than the main ram, and as a result the pressure starts to build up rapidly in the pull-back ram before the pressure on the main ram has been lowered materially. This produces a substantial shock in the hydraulic system and such shock causes severe wear in the pump.

An object of this invention is to provide an improved hydraulic system for presses and the like, with which the press may be reversed without material shock in the hydraulic system, and with a reduction of wear in the pump; which will not materially decrease the rapidity of operation of the press; which will not require material alteration of existing hydraulic circuits; and which will be relatively simple, practical, efficient and inexpensive.

Other objects and advantages will be apparent from the following description of several embodiments of the invention, and the novel features will be particularly pointed out hereinafter in connection with the appended claims.

In the accompanying drawings:

Fig. 1 is a plan, partly in section, of part of an ordinary hydraulic system, including a variable delivery, reversible pump modified in accordance with this invention;

Fig. 2 is a similar plan of a modification of the arrangement shown in Fig. 1;

Fig. 3 is a schematic diagram illustrating a modification of the invention in which a reversing valve is employed with a unidirectional pump; and

Fig. 4 is a similar schematic diagram, and illustrating still another embodiment of the invention but also using a reversing valve to accomplish reversals of travel of the platen.

In the embodiment of the invention illustrated in Fig. 1, the liquid for the hydraulic system is supplied by a reversible variable delivery pump 1. Some of such pumps are known as the "Hele-Shaw" type, and some are known as radial piston type pumps, but inasmuch as such pumps are in extensive use and are well known, a detailed description will be omitted. Such pumps commonly employ a shiftable yoke or flow controlling

member 2, and by shifting this yoke or controlling member in opposite directions through a central position, the direction of delivery of the pump may be reversed and its rate of delivery also varied. Connected to one side of the yoke or controlling member 2 are a pair of control rods 3, which extend outwardly from one end of the pump and are connected to a yoke or cross bar 4.

Extending from the yoke or controlling member 2 of the pump in the opposite direction from the pump housing are two control rods 5 which extend loosely through apertures 6 in a yoke or bar 7. The rods 5 are provided, intermediate of their ends, with enlargements 8 against which the yoke or bar 7 abuts. The ends 9 of the rods 5, which are outwardly beyond the enlargements 8, are of smaller diameter than the enlargements 8. The ends 9 of the rods 5 are threaded and carry nuts 10 threaded thereon. Helical compression springs 11 are mounted on the rod ends 9 between the nuts 10 and another yoke or bar 12, which is slidably mounted on the rod ends 9 so as to abut against the opposite ends of the enlargements 8. The yoke or bar 12 has apertures 13 through which the rod ends 9 loosely extend. The springs 11 thus urge the yoke or bar 12 against the enlargements or heads 8 of the rods 5.

The yoke or bar 12 is also provided with an opening 14 through which loosely extends a bolt or cap screw 15 having a head 16 bearing against the yoke 12, and having its other end threadedly connected to a tubular projection from a piston 17 which operates in a cylinder housing 18. A nut 19 is threaded on the bolt 15, and a helical compression spring 20 is disposed between the nut 19 and the face of the yoke or bar 12 on the opposite side from the head 16 of the bolt. The spring 20 yieldingly urges the yoke or bar 12 against the head 16 of the bolt 15.

By operating the piston 17 in the direction B in Fig. 1, the spring 20 will resiliently and yieldingly urge the yoke or bar 12 in the same direction, and by the pressure on the heads or enlargements 8 will urge the rods 5 yieldingly in the same direction. By moving the piston 17 in the opposite direction, that is, in the direction A in Fig. 1, the head of the bolt 15 will pull the yoke 12 and compress the springs 11, and thus exert a resilient pull on the yoke rods 5. Thus by operating the piston 17 in opposite directions, a yielding, resilient pressure will be exerted on the control member or yoke 2 tending to shift it in one direction or the other and thus reverse the direction of delivery of the pump. When the

piston 17 is moved in the direction A in Fig. 1, the yoke or controlling member 2 will be urged or shifted in a direction to cause delivery of the pump in the direction C through pipe 21, and when the piston 17 is moved in the direction B the yoke or controlling member 2 will be shifted in a manner to cause delivery of liquid by the pump in the direction D to pipe 22.

Extending from one side of the pump housing 1 is a small cylinder housing 23, and a piston 24 extends into this housing 23 through the open, outer end thereof, so as to reciprocate therein in the manner of a ram. The outer end of the rod or piston 24 is threaded and extends through the yoke 4 and nuts 25 which are threaded on the piston or rod 24 on opposite sides of the yoke 4 adjustably position the piston or small ram 24 with respect to the yoke 4. The inner end of the piston 24 is reduced in diameter slightly as at 26. A pipe 27 opens into the chamber 28 of the housing 23 at a point beneath the piston 24, and connects the chamber 28 with the pipe 21.

A similar housing 29 extends from the opposite side of the pump housing 1, and has a cylinder chamber 30 in which another piston or small ram 31 is received so as to extend outwardly therefrom. The ram 31 is threaded at its outer end and passes through the yoke 7 and nuts 32 threaded on the yoke 6 on opposite sides of the yoke adjustably secure the piston to the yoke 7. By adjusting the nuts 25 and 32 along the pistons or rams 24 and 31 respectively, the pistons 24 and 31 may be individually adjusted endwise with respect to the yokes 4 and 7. The chamber 30 is connected by a pipe 33 to the pipe 22.

In the base of the small housing 23 is another chamber 34 in which is mounted a piston 35 of considerably larger diameter than ram 24 and which has a stem 36 that projects into the chamber 28 and also acts as a small ram in the chamber 28. The chamber 34 is connected by a pipe 37 to the pipe 22 of the pump. Similarly the housing 29 has at its inner end another chamber 38 in which reciprocates a piston 39 of considerably larger diameter than the ram 31 and which also has a stem or reduced extension 40 which extends into the chamber 30 and acts as a ram therein. Chambers 34 and 38 have vents 41 and 42 respectively therein at the outer ends of those chambers. The chambers 34 and 38 are larger than the chambers 28 and 30 for a purpose which will appear shortly. The chamber 38 is connected by a pipe 43 to the pipe 21. The pipes 21 and 22 of the pump are connected in the usual manner to the main and pull-back rams of a press as usual in press systems.

When the yoke or control member 2 is shifted through center position in the direction A in Fig. 1, the pump will deliver fluid under pressure through the pipe 21 to one of the rams, such as the main ram, and the pipe 22 is then the suction pipe which withdraws liquid from the pull-back ram. When the yoke or control member 2 is shifted through center position in the direction B in Fig. 1, the delivery of the pump will be through pipe 22 and the pipe 21 will then act as the intake or suction pipe for the pump. The cylinder housing 18 is divided by the piston 17 into end chambers 44 and 45. An operating fluid is delivered to the chamber 44 by a pipe 46, and similarly a fluid under pressure is supplied to the chamber 45 through a pipe 47.

The pipes 46 and 47 lead to any suitable controlling mechanism by which the piston 17 may be operated in one direction or the other, de-

pending upon whether fluid under pressure is admitted through pipe 46 or 47. When operating fluid is admitted through either of the pipes 46 or 47, the other pipe of that pair would, of course, be vented and the pressure difference on opposite faces of the piston 17 will cause it to reciprocate in the direction A or B in Fig. 1.

Considering now the operation of this system, let it be assumed that the pipes 21 and 22 of the pump are connected into a hydraulic circuit leading to the main and pull-back rams respectively of a hydraulic press, as usual in such systems, it being understood that suitable and well known equalizing mechanism, not shown, is included in the hydraulic circuit so as to compensate for the differences in volumes of operating fluid in the main and pull-back cylinders. If it is desired now to cause a pressing or forward actuation of the platen of the press, a compressed fluid is admitted through pipe 46 to chamber 44 and the pipe 47 is at the same time vented. The pressure in chamber 44 forces the piston 17 in the direction A in Fig. 1 and the head 16 on the bolt 15 pulls the yoke 12 against the action of the springs 11. The springs 11 then supply a resilient pressure of the yoke rods 5 tending to shift the yoke or control member 2 in the direction A and cause delivery of the liquid from the pump through the pipe 21 to the main ram. Simultaneously the pipe 22 withdraws liquid from the pull-back ram.

When the pressure on the main ram, which will correspond substantially to the pressure in the pipe 21, reaches or exceeds a predetermined pressure, this pressure, because of the connection of the pipe 21 through pipe 27 to the chamber 28, exerts a corresponding pressure per unit area on the ram 24, thus tending to shift the yoke or control member 2 of the pump back towards neutral or no delivery position. This decreases the delivery rate of the pump and when the pressure in chamber 28 has increased sufficiently, it will shift the yoke 2 either into the neutral or no delivery position or just sufficiently out of that position to cause delivery of just sufficient liquid by the pump into pipe 21 to maintain the desired pressure. This movement of the yoke of the piston 24 is resisted by the rods 3 which lead to the yoke 2, and also by the springs 11. The stress in the springs 11 thus determines the pressure at which the piston or ram 24 will operate the yoke 2 into substantial no delivery position, that is, it determines the pressure which will be maintained in the pipe 21.

When the operator desires to reverse the pump, to cause a retraction of the platen, the pipe 46 is vented and fluid under pressure admitted through pipe 47 to chamber 45. This forces the piston 17 in the direction B in Fig. 1, and the piston 17 acting through the bolt 15 compresses the spring 20 and urges the yoke 12 in the direction B. The yoke 12 bearing on the enlargements or heads 8 of the yoke rods 5 urges the latter, and thereby the controlling member or yoke 2, in the direction B to shift the yoke in a direction to cause delivery of the pump through the pipe 22 in the direction D instead of the pipe 21, and the pipe 21 then becomes the intake pipe for the pump. This invention contemplates the idea of preventing the operation of the pump on full stroke in the reverse position until after the pressure in the pipe 21 has fallen down to a relatively low pressure, to avoid shock in the hydraulic system and thus reduce wear

in the pump. The means by which this is accomplished will now be explained.

The pressure in the pipe 21 was also transmitted through the pipe 43 to the chamber 38, and this pressure in chamber 38 was exerted on the large piston 39 so as to force it outwardly until it engaged the outer end of the chamber 38, as shown in full lines in Fig. 1. The free end of the reduced piston stem 40 in the chamber 30 is in the path of movement of the piston 31 when the latter is being moved with the yoke or controlling member 2, because the heads 8 of the rods 5 bear directly on the yoke 7 and force the piston 31 inwardly during this reversal. It will be understood that at this time, the pressure in the chamber 30 will be the same as in the pipe 22 which is the suction pipe of the pump, and therefore relatively low. The length of the piston stem 40 from yoke 7 is such that stem 40 will engage the inner end of the piston 31 just after the yoke 2 has slightly passed the neutral or no delivery position and started a very small delivery rate in the direction to deliver fluid into the pipe 22.

The pressure in chamber 38 which is the same as in pipe 21 leading to the main ram, will oppose further movement of the piston 31 under the urging of the spring 20 until the pressure in the pipe 21 and chamber 38 have fallen to a relatively low pressure, whereupon the pressure of the spring 20 is then sufficient to overcome the pressure on piston 39, and the piston 31 will then continue its movement by forcing the piston 39 toward the pump, that is, inwardly in the housing 29. The pump will then go on full stroke. It will be observed that while a slight reversal occurs immediately following operation of the piston 17 in the direction B in Fig. 1, the movement of the yoke or control member is limited to a position just beyond reversal position, so that the pump delivers only at a very slow rate until the pressure on the main ram, which is the same as in the pipe 21, has fallen sufficiently, and then the yoke is shifted into full stroke position automatically.

This avoids any objectionable shock in the hydraulic system caused by reversal of the pump while the pressure on the main ram still remains high. The liquid from the pump will then be delivered in the direction D through pipe 22 to the pull-back ram and removed through the main ram to the pipe 21. This will continue until the pressure in the pull-back ram builds up at the end of the return movement and since this pressure will be the same as in the pipe 22, it will be communicated through the pipe 33 to the chamber 39. When the pressure on piston 31 is sufficient, it will force the piston 31 outwardly, and through the yoke 7 bearing on the heads 8 of the rods 5, will urge the main yoke or control member 2 in a direction to curtail the rate of delivery. This movement of the rods 5 and of the piston 31 is opposed by the spring 20, and when the pressure has been built up sufficiently to overcome the spring 20, the latter will be compressed to such an extent that the yoke or controlling member 2 of the pump will be positioned to provide just sufficient delivery to maintain the selected pressure in the pipe 22.

When the operator desires to reverse the pump and cause another operation of the main ram, the pipe 47 is vented and operating fluid under pressure delivered through pipe 46 to chamber 44. This forces the piston 17 in the direction A and compresses the springs 11, thereby urging

the yoke rods 5 in a direction to shift the pump yoke 2 into reversed position. The pressure on the pull-back ram and pipe 22 was, however, communicated through the pipe 31 to the chamber 34, so that the piston 35 was held outwardly, as shown in full lines in Fig. 1, and the piston stem 36 opposed the movement of the piston 24 beyond a position in which the yoke 2 was at a low delivery rate in the reverse position.

10 The pump will thus be held at a low delivery rate in a reverse position in which it delivers to the pipe 21, until the pressure on the pull-back ram, and thus in pipe 22, has fallen sufficiently that the pressure of the springs 11 can overcome the pressure on the piston 35 and permit automatic continuance of the reversal, which places the pump on full stroke, delivering liquid into the pipe 21. Thus we have a complete cycle of movement. The pump is driven continuously by 15 any suitable source of power, such as through a coupling 48 from a motor 49. By shifting the pistons 21 and 34 in their yokes 7 and 4 respectively, the extent to which the pump moves on stroke at each reversal before the pressure falls 20 may thus be varied to some extent.

25 Referring now to the embodiment of the invention shown in Fig. 2, the construction and arrangement is the same as in Fig. 1, except that the chambers 34 and 38 and pistons 35 and 39 are omitted, and certain other changes made 30 which will now be explained. It will be understood that the parts in Fig. 2 which are the same as corresponding parts in Fig. 1 will be given the same reference characters, and will not be described in detail. In this embodiment of the invention, the piston 17 is provided with another rod 50 which extends outwardly of the cylinder housing 18, and the outer end of this rod 50 is connected by a pin 51 to one arm of a lever 52. 35 40 The connection of the pin 51 to the lever 52 is by a slot, not shown, in lever 52 and running in a direction lengthwise thereof so as to provide for lost motion.

45 The lever 52 is pivoted at 53 and carries another arm 54. Similar chambers 55 and 56 are arranged on opposite sides of the arm 54. In the chamber 55 is arranged the piston 57 having a stem 58 extending outwardly therefrom into a position adjacent one face of the arm 54. A 50 piston 59 operates in the cylinder 56 and has a stem 60 extending outwardly thereof into a position adjacent the other face of the arm 54. When the pistons 57 and 59 are both forced outwardly as shown in Fig. 2, there will be sufficient 55 clearance between the outer ends of the stems 58 and 60 and the arm 54 to allow limited movement of the arm 54 which is sufficient, through its connection to the pump yoke, to shift the pump yoke through no delivery position a short 60 distance to opposite sides thereof, and place the pump on very short stroke when delivering in either direction.

65 The stems 58 and 60 prevent movement of the pump yoke or control member into full stroke positions in both directions. Thus when the piston 17 is moved in the direction B in Fig. 2, the arm 54 will engage the stem 60 and be limited thereby to such an extent that the pump yoke only goes on stroke slightly to deliver liquid 70 into pipe 21 at a relatively small rate. Similarly when the pump is reversed, the stem 58 will limit movement of arm 54 and consequently of the piston yoke to allow the pump to go only on a short stroke in the opposite direction. The cylinder chamber 55 is connected by a pipe 61 to 75

the pipe 22, and chamber 56 is connected by pipe 62 to the pipe 21. Thus the pistons 57 and 59 function in the same manner as the pistons 35 and 39 respectively of Fig. 1, and the operation will otherwise be the same as described for Fig. 1.

Referring now to the embodiment of the invention shown in Fig. 3, the pump 63, as illustrated, is of the uni-directional but variable delivery type, which has a yoke 64 which varies the rate of delivery of the pump as it is shifted. A spring 65 acting on the yoke 64 tends to shift it into the full stroke position in which the pump delivers liquid at its maximum rate into the pipe 66, and liquid is supplied to the pump from the reservoir 67 by a pipe 68. The pipe 66 is connected to a port 69 of a reversing valve 70. A valve element 71 reciprocates in the valve housing 70 and is provided with lands 72 and 73 which are spaced apart along the valve element.

A pipe 74 connects a port 75 of the valve 70 with the pull-back ram chamber 76, and similarly a pipe 77 connects the main ram cylinder 78 to a port 79 in the valve housing 70. The pipe 68 is also connected by a branch 80 to the opposite ends of the valve 70 to serve as exhaust connections thereto. When the valve element 71 is in an intermediate position, such as shown in full lines in Fig. 3, the lands 72 and 73 will be in alignment with the ports 75 and 79 respectively. The land 72 completely closes the port 75, and the land 73 is bevelled so that its effective peripheral surface does not completely close or bridge the port 79. Liquid delivered to the valve housing through pipe 66 may thus circulate around the land 73 at port 79 and pass through the adjacent end of the valve housing back to pipe 80, thence to the reservoir 67 or through the pipe 68 to the intake side of the pump.

When the valve element 71 is shifted upwardly in Fig. 3 to place the land 73 between the port 79 and the opening to pipe 80, the land 72 will uncover port 75 and be disposed between ports 75 and 69. The land 73 will thus prevent escape of the liquid delivered by the pump through the pipe 80 and consequently it will pass through pipe 77 to the main ram cylinder 78 and cause an advancement of the ram 81. At the same time, land 72 uncovers port 75 and connects pipe 74 to pipe 80 allowing escape of liquid from the pull-back cylinder 76. When the valve element 71 is moved downwardly in Fig. 3 from the position shown in full lines, it similarly moves the land 73 between the ports 69 and 79 and positions the land 72 between the port 75 and the lower exhaust to pipe 80. Then the delivery from the pipe 66 will pass through the pipe 74 to the pull-back cylinder 76, and liquid from the cylinder 78 will pass through the pipe 77, and the upper end of the valve housing in Fig. 3 to the branch pipe 80, and thence back to the pipe 68 or the reservoir.

Such reversing valves are well known in the art, and any suitable type may be employed. In the simple illustration given, the outer end of the valve stem 71 carries a pin 82 which runs in a slot 83 in a handle or operating lever 84, which is pivoted at 85, and this handle 84 may be secured in different adjusted positions in any suitable manner. It will be understood that this reversing valve may, if desired, be controlled or operated in the manner shown in my copending application Serial No. 204,375, filed April 26, 1938, but any other type of reversing valve control may also be employed.

In order to prevent shock in the system when 75

the ram 81 is reversed, that is, when the reversing valve is operated, I provide piston 86 which extends from the yoke 64 of the pump into a cylinder 87. This cylinder 87 is connected by 5 pipes 88, 89, free check valve 90 and pipe 91 to the delivery pipe 66 of the pump. The pipe 88 is also connected by a pipe 92, a pressure relief valve 93 and a pipe 94 to the delivery pipe 66 of the pump. The pressure relief valve 93 is of 10 the type which opens to pass liquid from the pipe 66 to the pipe 92 when the pressure in pipe 66 exceeds a predetermined pressure for which the valve 93 is set. Such pressure relief valves are common in the art, and a detailed description is therefore believed unnecessary. The valve 93 thus passes liquid in the direction of the arrow *a* when the pressure in pipe 66 is sufficiently high, and the free check valve 90 opens freely to pass liquid in the direction of the arrow *b* but closes automatically to prevent reverse flow.

Also extending into the chamber 87 is a small ram or stem 95 which is carried by a relatively large piston 96 that operates in a cylinder chamber 97. The end of the chamber 97 adjacent the stem 95 is vented as at 98. The chamber 97, at the opposite side of the piston 97 from the stem 95, is connected by a pipe 99 and a free check valve 100 to the pipe 92, and also through a free check valve 101 and a pipe 102 to the pipe 77 leading to the main ram cylinder 78. The free check valve 100 opens freely to pass liquid in the direction of the arrow, but closes automatically to prevent reverse flow, and the free check valve 101 also opens freely to pass liquid in the direction of the arrow but closes automatically to prevent reverse flow.

In the operation of this embodiment of the invention, let it be assumed that the reversing valve 71 is at the intermediate or neutral position shown in Fig. 3, and then the liquid from the pump will be circulated idly through the reversing valve, and the pipe from the pull-back ram 76 will be closed by the land 72, thereby preventing any movement of the ram 81. Any liquid trapped in the chamber 87 may escape through pipes 88, 89, valve 90 and pipe 91 to the pipe 66, and the spring 65 thus shifts the yoke 64 of the pump into full stroke or maximum delivery position. If now the operator moves the valve element 71 in an upward direction, in Fig. 3, to cause an advance or working stroke of the ram 81, the pipe 66 will be connected to pipe 77 and the pipe 74 from pull-back ram will be connected to the branch return pipe 80 during the advance or working stroke of the platen.

When the ram 81 encounters resistance, the pressure in chamber 78 will build up, and consequently the back pressure on the pipe 66 will build up. The valve 90 then automatically closes and when the pressure in the pipe 66 exceeds the pressure for which the valve 93 is set, liquid will also pass from the pipe 66 through pipe 94, pressure relief valve 93, pipes 92 and 88 to the cylinder chamber 87, and this pressure will force the piston 86 of the yoke in a direction to compress the spring 65 and move the yoke 64 in a direction to curtail the rate of delivery. When the pressure in chamber 87 has built up sufficiently to overcome fully the spring 65, the yoke 64 of the pump will have been shifted into a position such that there is just sufficient delivery to maintain that predetermined pressure on the pipe 66. At the same time, the liquid from the pipe 92 will also pass through free check valve 100 and pipe 99 to chamber 97, and would also pass through check

valve 101 except for the fact that the pressure in pipe 102 at the opposite side of the valve 101 will be substantially the same as in pipe 66. The pressure in chamber 97 will force the piston 96 to the right in Fig. 3, but it does not quite engage the yoke piston 86.

When the operator desires to reverse the press, he moves the valve element 71 downwardly in Fig. 3 to place the land 72 below the port 75 and shift the land 73 into a position between the ports 69 and 79. The pipe 66 will then be connected to the pipe 74, so as to deliver fluid to the pull-back cylinder 76, and pipe 77 to the main ram cylinder 78 will now be connected through the pipe 80 to the reservoir 67 and to the intake side of the pump. The pressure at this time in the pull-back cylinder is relatively low, and consequently the pressure in pipe 66 would be relatively low, so that the spring 65 then tends to shift the yoke 64 of the pump into full or maximum stroke position which would cause objectionable shock in the hydraulic system. The spring 65 will shift the yoke 64 until the piston 86 of the yoke engages the stem 95 of the piston 96, which will be at a point such that the yoke will be in a position to set the pump for a relatively low rate of delivery. The piston 96 prevents further movement of the yoke into full delivery position.

The liquid will escape from the main ram cylinder 78 through pipe 77, and as soon as the pressure in the main cylinder 78 falls sufficiently, which requires a short interval of time, the valve 101 will open and pass liquid from the chamber 97, thus releasing the pressure on piston 96, whereupon it is moved by the action of spring 65, which forces the yoke into full stroke position. The valve 100 closes, however, automatically to compel release of the pressure on piston 96 through the pipe 77, valve 101 and pipes 102 and 77. Thus the pump will be prevented automatically from going on full stroke until the pressure in the main ram cylinder has fallen to a reasonably low pressure.

The embodiment of the invention shown in Fig. 4 is similar to that shown in Fig. 3, except that the cylinder 97 is connected into the hydraulic circuit in a slightly different manner. Parts which are identical in Figs. 3 and 4 are given the same reference characters. The reversing valve is the same as in Fig. 3, except that an addition is made thereto, either through a separate housing or as a part of the same housing. To the valve 70a which corresponds generally to the valve 70 of Fig. 3 is added a chamber 103, and the valve element 71a has an extension 104 passing through a wall 105 into the chamber 103 where it carries a land 106. The pipe 77 has a branch 107 leading to port 108 in the chamber 103, and another port 109 in the chamber 103 is connected by a pipe 110 to the chamber 97. The pipes 99, 102 and valves 100 and 101 in Fig. 3 are of course omitted. The chamber 103 is provided with a vent 111 at its lower end in Fig. 4.

When the valve element 71a is in the intermediate position shown in Fig. 4, which corresponds to the intermediate position shown in Fig. 3, the pump of course circulates liquid idly through the reversing valve, and the ram 81 is held in stationary position. When the reversing valve element 71a is moved upwardly in Fig. 4 to cause an advance or working stroke of the platen, the land 106 will move upwardly in the chamber 103 and keep the port 108 closed, and thus keep the pipe 110 closed in the port 109. When the pressure in the pipe 66 builds up, due to resistance encountered by the ram 81, the pressure relief

valve 93 will open and pass liquid to the chamber 87 and cause a resetting of the pump yoke to no delivery position or just sufficiently on stroke to maintain the desired pressure, as explained in connection with Fig. 3.

When the reversing valve is operated to reverse the system, and cause a retraction of the ram 81, the land 106 will be carried downwardly in Fig. 4, so as to uncover the port 108 just prior to or at about the same time that the pump is connected by pipe 66, the reversing valve and pipe 74 to the pull-back ram cylinder 76. This connects the pipe 77 to pipe 110 and the chamber 97, so that the chamber 97 is immediately placed under the same pressure as the main ram chamber 78. This forces the piston 96 to the right in Fig. 4 and forcibly moves the yoke piston 86 to a position in which it places the pump only slightly on stroke. As soon as the pressure in the main ram chamber 78 falls, the pressure in chamber 97 will fall and the spring 65 can then displace the piston 96 to the left in Fig. 4 and shift the yoke of the pump back into full stroke position. Thus, upon actuation of the reversing valve to retract the ram, the pump will be prevented from going on stroke until the pressure in the main ram has fallen to a desired extent. When the reversing valve is moved into either the intermediate or upper position in Fig. 4, the port 108 will be closed, which removes the chamber 97 from responsiveness to the pressure in the pipe 77.

It will be understood that various changes in the details and arrangements of parts, which have been herein described and illustrated in order to explain the nature of the invention, may be made by those skilled in the art, within the principle and scope of the invention, as expressed in the appended claims.

I claim as my invention:

1. In a hydraulic motor system of the type employing a reversible, variable delivery pump with a controlling member shiftable to reverse the direction of delivery of the pump, and to vary the rate of delivery thereof, the improvement in the control of said member which comprises means yieldingly urging said member in opposite directions to reverse the pump selectively, and means responsive to the hydraulic pressure of the fluid delivered by the pump for preventing movement of said member beyond a selected minor extent past reversing position until the pressure of the fluid delivered by the pump prior to the attempted reversal falls below a predetermined selected pressure.

2. An improved control for a variable delivery, reversible pump having a pair of pipes, each of which serves as a delivery pipe when the other serves as an intake pipe, depending upon the direction of delivery of said pump, said pump having a controlling member shiftable to vary the rate and direction of delivery of the pump, and a hydraulic device responsive to pressure in one of said pipes for preventing movement of said controlling member into full stroke position for delivery to the other of said pipes but allowing movement through reversing position into a partial delivery position to said other pipe while the pressure in said one pipe exceeds a predetermined pressure, and releasing said member for continued movement into full stroke position when the pressure in said one pipe falls to a selected low pressure.

3. In a hydraulic press system, a reversible, variable delivery pump having a controlling

member shiftable to vary the direction and rate of delivery of the pump, means connected to said member for operating it in opposite directions to reverse the pump and having resilient connections to said member, and means responsive to the pressure in the pipe connections to the pump for restricting the movement of said member beyond a position causing a partial rate of delivery during a reversal and after reversal, until the fluid pressure in the delivery pipe of the pump before reversal has fallen to a predetermined extent, said pressure responsive means including hydraulically actuated abutments shiftable by hydraulic pressure into positions confining movement of said member to a restricted partial delivery zone having limits on opposite sides of the neutral delivery position.

4. An improved control for a reversible, variable delivery pump having a controlling member shiftable in opposite directions to reverse the pump and operable when in intermediate positions to control the rate of delivery of said pump, which comprises yieldable means connected to said member for urging said member in opposite directions to reverse the pump, abutments operable into and out of positions to oppose movement of said member into full delivery positions, hydraulic means for shifting said abutments into obstructing positions in which they limit the movement of said member to partial delivery positions in both directions, the hydraulic means for one of said abutments being controlled by the delivery from one delivery pipe of the pump, and for the other abutment being controlled from the other delivery pipe of the pump, the delivery pipe of the pump to which each said hydraulic means is connected being that which is the delivery pipe before reversal of delivery of the pump and when the controlling member was on the opposite side of no-delivery position from that occupied when that particular abutment is effective to limit movement of said member, whereby pressure in the pipe of the pump before reversal will limit movement of the controlling member beyond reversal to a specified low rate delivery position until the pressure in the previous delivery side of said pump has fallen to a predetermined extent.

5. In a hydraulic motor system of the type employing a variable delivery, reversible pump with a pair of pipes, each of which serves as an intake pipe when the other serves as a delivery pipe, depending upon the direction of delivery of the pump, and with a controlling member shiftable to vary the rate and direction of delivery of the pump, that improvement in the control of said pump which comprises means for resiliently urging said member in either direction to set the pump for full delivery in one direction or the other, depending upon the direction of delivery desired, means responsive to the pressure of the fluid delivered by the pump through one of said pipes for limiting the movement of said controlling member to a selected portion only of its possible movement through delivery reversal position when discontinuing delivery through said one pipe and starting removal of fluid therethrough, until the pressure of the fluid in said one pipe has fallen to a predetermined low pressure.

6. In a hydraulic motor system of the type employing a reversible, variable delivery pump having a controlling member shiftable in opposite directions to vary the direction and rate of delivery of the pump, and a pair of pipes, each

of which serves as an intake pipe when the other serves as a delivery pipe, the improved control for said controlling member which comprises means resiliently connected to said member for operating it in opposite directions to reverse the direction of delivery of the pump, and means responsive to the pressure in the pump pipes for restricting the movement of said member beyond a position causing a partial rate of delivery during a reversal and after reversal until the fluid pressure in the delivery pipe of said pump before reversal has fallen to a predetermined extent.

5 7. In a hydraulic motor system of the type employing a reversible, variable delivery pump with a controlling member shiftable to vary the direction and rate of delivery of the pump and with pipe connections to the pump, each of which serves as an intake pipe for the pump when the other is a delivery pipe, the improved 15 control for said member which comprises operating means resiliently connected to said member for operating it in opposite directions to reverse the pump, and means responsive to the pressure in each of said pipes for restricting the movement of said member beyond a position causing a partial rate of delivery during a reversal and after reversal, until the fluid pressure in the delivery pipe of the pump before reversal has fallen to a predetermined extent, said pressure responsive means including hydraulically actuated 20 abutments shiftable by hydraulic pressure into positions for confining movement of said member to a restricted, partial delivery zone having limits on opposite sides of the neutral delivery 25 position of said member.

8. In a hydraulic motor system of the type employing a reversible, variable delivery pump having a controlling member shiftable in opposite directions to vary the direction and rate 40 of delivery of the pump, and a pair of pipes, each of which serves as an intake pipe when the other serves as a delivery pipe, the improved control for said controlling member which comprises an operating member, an arm having an aperture 45 through which said operating member slidingly extends, an abutment on said operating member engageable with one face of said arm, a spring acting between said operating member and said arm for yieldingly urging said abutment against said arm, said arm also having another aperture through which said control member slidingly extends, said control member also having a shoulder engageable against that face of said arm which is engaged by said abutment, a spring acting between said control member and said arm for resiliently urging said arm against said shoulder, and means responsive to the pressure in each of 50 said pipes for restricting movement of said control member in a reversing direction, which would discontinue delivery of fluid under pressure to one of said pipes and draw fluid therefrom, to a part only of the possible movement of said control member beyond neutral position during such reversing movement until the fluid pressure in said pipe serving as a delivery pipe prior to such reversal has fallen to a desired extent.

9. In a hydraulic motor system of the type employing a reversible, variable delivery pump having a controlling member shiftable in opposite directions to vary the direction and rate of delivery of the pump, and a pair of pipes, each of which serves as an intake pipe when the other serves as a delivery pipe, the improved control for said controlling member which comprises an operating member, an arm having an

aperture through which said operating member slidingly extends, an abutment on said operating member engageable with one face of said arm, a spring acting between said operating member and said arm for yieldingly urging said abutment against said arm, said arm also having another aperture through which said control member slidingly extends, said control member also having a shoulder engageable against that face of said arm which is engaged by said abutment, a spring acting between said control member and said arm for resiliently urging said arm against said shoulder, a pair of pistons, a chamber for each piston, a pair of plungers, one operable on said controlling member to urge it in one direction and the other operable on said controlling member to urge it in the opposite direction, one of said pistons being operable to oppose movement of one of said members in one reversing direction beyond a part only of its possible movement past neutral, no-delivery position, the other of said pistons being similarly operable to oppose movement of said one of said members in the opposite reversing direction beyond a part only of its possible movement past said no-delivery position, means for operating each of said pistons into opposing position and responsive to fluid pressure in the pump pipe which is the delivery pipe before the reversal movement which is opposed by that piston, and individual means for operating each of said plungers, each of which individual means being responsive to the fluid pressure in that pump pipe which will cause the control member to be shifted into said no-delivery position when a predetermined pressure in said last-mentioned pipe is reached.

10. In a hydraulic motor system of the type employing a reversible, variable delivery pump having a controlling member shiftable in opposite directions to vary the direction and rate of delivery of the pump, and a pair of pipes, each of which serves as an intake pipe when the other serves as a delivery pipe, the improved control for said controlling member which comprises an operating member, an arm having an aperture through which said operating member slidingly extends, an abutment on said operating member engageable with one face of said arm, a spring acting between said operating member and said arm for yieldingly urging said abutment against said arm, said arm also having another aperture through which said control member slidingly extends, said control member also having a shoulder engageable against that face of said arm which is engaged by said abutment, a spring acting between said control member and said arm for resiliently urging said arm against said shoulder, a pair of cylinders, each having a relatively large chamber closed at one end and opening outwardly at the other end through a relatively small bore, a piston in each chamber, a plunger in each bore and movable therein into and out of engagement with the piston in the connected chamber, one of said plungers being operable on said control member to urge it in one direction and the other of said plungers being operable on said control member to urge it in the opposite direction, a conduit connecting the closed end of each chamber to one of said pump pipes, another conduit connecting the inner end of the bore opening outwardly from that same each chamber to the other of said pump pipes, each of said another conduits being connected to that pump pipe which serves as the intake pipe for said pump before the control member is shifted through

neutral position in a direction opposed by the piston of the same cylinder.

11. In a hydraulic motor system of the type employing a reversible, variable delivery pump having a controlling member shiftable in opposite directions to vary the direction and rate of delivery of the pump, and a pair of pipes, each of which serves as an intake pipe when the other serves as a delivery pipe, the improved control for said controlling member which comprises an operating member, resilient connecting means between said members, a pair of cylinders, each having a relatively large chamber closed at one end and opening outwardly at the other end through a relatively small bore, a piston in each chamber, a plunger in each bore and movable therein into and out of engagement with the piston in the connected chamber, one of said plungers being operable on said control member to urge it in one direction and the other of said plungers being operable on said member to urge it in the opposite direction, a conduit connecting the closed end of each chamber to one of said pump pipes, another conduit connecting the inner end of the bore opening outwardly from that same each chamber to the other of said pump pipes, each of said another conduits being connected to that pump pipe which serves as the intake pipe for said pump before the control member is shifted through neutral position in a direction opposed by the piston of the same cylinder.

12. An improved control for a reversible, variable delivery pump having two pipes and a controlling member shiftable back and forth to vary the direction and rate of delivery of the pump as between said pipes, which comprises means operable on said member, for yieldingly urging it through neutral, no delivery position selectively in either direction to place the pump on full delivery in either direction, and means responsive to the hydraulic pressure in one of said pipes for automatically limiting the movement of said member by said urging means to a selected, partial and incomplete movement beyond neutral, no delivery position in a direction to set the pump for delivery to the other of said pipes, until the pressure in said one pipe drops below a selected, predetermined pressure, but operable automatically to release said member for free and continued movement in the same direction into full delivery position when the pressure in said one pipe drops below said predetermined pressure and said pump is delivering to said other pipe.

13. An improved control for a reversible, variable delivery pump having two pipes and a controlling member shiftable back and forth to vary the direction and rate of delivery of the pump as between said pipes, which comprises means operable on said member, for yieldingly urging it through neutral, no delivery position selectively in either direction to place the pump on full delivery in either direction, means responsive to the hydraulic pressure in one of said pipes for automatically limiting the movement of said member by said urging means to a selected, partial and incomplete movement beyond neutral, no delivery position in a direction to set the pump for delivery to the other of said pipes, until the pressure in said one pipe drops below a selected, predetermined pressure, but operable automatically to release said member for free and continued movement in the same direction into full delivery position when the pressure in said one pipe drops below said predetermined pres-

sure and said pump is delivering to said other pipe, and means responsive to the pressure in said one pipe for also shifting said member into no delivery position against the action of said urging means upon the attainment of a predetermined pressure in said one pipe while said pump is delivering into said one pipe.

14. An improved control for a reversible, variable delivery pump having two pipes and a controlling member shiftable back and forth to vary the direction and rate of delivery of the pump as between said pipes, which comprises an operating element, resilient means interposed between said member and element for urging said member solely in one direction to cause delivery at a desired rate into one pipe and yieldingly holding it so urged when said element is operated into and remains in one position, additional resilient means also interposed between said member and element for urging said member solely in the other direction to cause delivery at a desired rate into the other of said pipes and yieldingly holding it so urged when said element is operated into and remains in another position, and means responsive to the hydraulic pressure in said one pipe for temporarily limiting movement of said member by said additional resilient means to a position beyond no delivery position, but only sufficient to cause delivery at a part of its possible rate, when setting said pump for delivery to said other pipe, until the pressure in said one pipe drops below a selected, predetermined pressure, but operable automatically to release said member for free and continued movement in the same direction into full delivery position by said additional means, after the pressure in said one pipe has dropped below said predetermined pressure and said pump is delivering to said other pipe.

15. An improved control for a reversible, variable delivery pump having two pipes and a controlling member shiftable back and forth to vary the direction and rate of delivery of the pump as between said pipes, which comprises an operating element, resilient means interposed between said member and element for urging said member solely in one direction to cause delivery at a desired rate into one pipe and yieldingly holding it so urged when said element is operated into and remains in one position, additional resilient means also interposed between said member and element for urging said member solely in the other direction to cause delivery at a desired rate into the other of said pipes and yieldingly holding it so urged when said element is operated into and remains in another position, means responsive to the hydraulic pressure in said one pipe for temporarily limiting movement of said mem-

ber by said additional resilient means to a position beyond no delivery position, but only sufficient to cause delivery at a part of its possible rate, when setting said pump for delivery to said other pipe, until the pressure in said one pipe drops below a selected, predetermined pressure, but operable automatically to release said member for free and continued movement in the same direction into full delivery position by said additional means, after the pressure in said one pipe has dropped below said predetermined pressure and said pump is delivering to said other pipe, and means responsive to the pressure in either of said pipes for also automatically shifting said member, against the action of whichever of said resilient means has been yieldingly urging it into a delivery position, into no delivery position upon the attainment of a predetermined pressure in that pipe which causes said automatic shifting and into which said pump is discharging.

THOMAS F. STACY.
